UNITED STATES PATENT OFFICE.

WILLIAM BOOTH LUPTON, OF WINDERMERE, ENGLAND.

PAPER-HANGER'S TOOL.

Application filed May 20, 1922. Serial No. 562,466.

To all whom it may concern:

Be it known that I, WILLIAM BOOTH LUPTON, a subject of the King of Great Britain and Ireland, residing at 44 Limethwaite, 5 Heathwaite, Windermere, in the county of Westmoreland, England, have invented certain new and useful Improvements in and Relating to Paper-Hangers' Tools, of which the following is a specification.

10 This invention relates to paperhangers' tools and consists of an appliance for cutting and trimming the paper, the object of the invention being to enable the paperhanger to cut the paper to the desired 15 length, or width of overhang, when it is partly hung with an absolutely even cut and in an assured straight line.

The appliance consists of a flat plate of 20 relatively narrow width in proportion to its length, on one face of which are a plurality of longitudinally arranged grooves which are arranged in parallel relation to one edge of the plate—hereinafter referred to as the front edge—and to one another, and 25 at a predetermined distance from the front edge of the plate and from each other. To the other edge of the plate is attached a handle for supporting the plate in its working position the position of said handle in 30 relation to said plate being capable of being varied. On the free end of the handle is mounted a spike.

In the accompanying drawing which illustrates this invention:

35 Figs. 1 and 2 are views in plan and end elevation respectively of the appliance.

Fig. 3 is a view showing the method of 40 using the appliance for cutting the paper above a skirting board or the like which expression is intended to cover picture or dado rails, door frames, mantel pieces, etc.

Fig. 4 is a view showing the method of 45 using the appliance for trimming paper at ceiling heights.

Fig. 5 is a view of a suitable form of wheel 50 cutter for use with this appliance.

Fig. 6 is a view in transverse section of 55 the preferred form of cutter, and

Fig. 7 is a view—in transverse section on 60 an enlarged scale of the plate.

Throughout the views similar parts are 65 denoted by like numerals of reference.

The plate 1 which is preferably of rectangular form and may be of metal or any 70 other suitable material has on one of its faces—hereinafter referred to as the upper

face—three grooves 2, 3 and 4 which are arranged in parallel relation to the front edge 5 of the plate which is straight and to one another. The distance of the groove 60 2—nearest to the front edge of the plate—from said front edge is equal or approximately equal to the thickness of the plate. The other grooves are located at suitable distances apart and from the groove 2. 65

On to the back of the plate is fixed a bracket 6 to which is pivoted a rod 7 on which is screwed a handle 8 the free end of which is provided with a spike 9. On the rod 7 is also screwed a nut 10 for locking the handle in the desired position on the rod.

To enable the handle to be readily removed from the plate to facilitate packing and transport, or to enable the plate to be 70 used for tearing off paper in the desired hanging lengths, either the bracket 6 is attached to the plate 1 by screws 11 so that it—with the handle 8—can be readily detached, or the pin 12 by which the rod 7 80 is pivoted to the bracket 6 can be made easily removable.

The upper face of the plate 1 may conveniently be divided so as to form a measuring rule.

When using the appliance for cutting off the edge of the paper above a skirting board or the like the front edge of the plate 1 is placed on the top of said board and is supported in that position as shown in Fig. 3 90 by fixing the handle in the flooring by means of a spike 9, the adjustment of said handle enabling the plate to be kept level or approximately so irrespective of the height of the skirting board or the like. 95

When using the appliance at ceiling heights or in other places when there is no available support for the plate the appliance is supported by hand against the ceiling and the wall by means of the handle 8. To facilitate supporting the plate in this position the hinge connection between the rod 7 and the bracket 6 may be made in the form of a knuckle joint whereby the handle is retained in its most convenient position relative to the plate.

After the appliance has been fixed or is supported in position the edge of the paper is folded over the upper face of the plate and the waste is cut off by running the wheel along one of the 110 grooves to cut the paper to the desired length.

Any suitable type of wheel cutter

such as the one shown in Figs. 5 and 6 may be used.

By the use of this appliance the following advantages accrue:—(1) All paste is kept off the ceiling, friezes and woodwork. (2) The paperhanger can cut the paper to any desired length either to lap over the wood-work or to finish flush with the top of the skirting board or the like. (3) the same length of overlap can be assured with every length of paper. (4) The waste ends of the paper adhere to the plate and do not lie about the floor. (5) No paste can adhere to the papering brush as the woodwork is left dry and clean. (6) No special skill is required to operate the trimmer and a material saving of time is effected by its use, and lastly, the trimmer can be readily adjusted to suit any height of skirting board or the like.

What I claim is:—

1. A trimmer for paperhangers' use comprising a flat plate of relatively narrow width in proportion to its length, a plurality of longitudinally arranged grooves in parallel relation to one of the edges of the plate and to each other, said grooves being each located at a predetermined distance from one of the edges of the plate, and a handle mounted on said plate and adjustable in relation thereto.

2. A trimmer for paperhangers' use comprising a flat plate of relatively narrow width in proportion to its length, a plurality of longitudinally arranged grooves in parallel relation to one of the edges of the plate and to each other, said grooves being each located at a predetermined distance from one of the edges of the plate, a handle mounted on said plate and adjustable in relation thereto, and a spike carried by the free end of said handle.

3. A trimmer for paperhangers' use comprising a flat plate of relatively narrow width in proportion to its length, a plurality of longitudinally arranged grooves in parallel relation to one of the edges of the plate and to each other, said grooves being each located at a predetermined distance from one of the edges of the plate, a handle detachably mounted on said plate and adjustable in relation thereto, and a spike carried by the free end of said handle.

4. A trimmer for paperhangers' use comprising a flat plate of rectangular form and of relatively narrow width in proportion to its length, a plurality of longitudinally arranged grooves in parallel relation to the

front edge of said plate and to each other, said grooves being located at predetermined distances from the front edge of said plate, a bracket detachably mounted on the back edge of said plate a handle hinged to said bracket and adjustable in relation thereto, and a spike carried by the free end of said handle.

5. In a paperhangers' tool, the combination of a flat plate of relatively narrow width in proportion to its length, a plurality of longitudinally arranged grooves in parallel relation to the front edge of said plate and to each other, said grooves being located at predetermined distances from the front edge of said plate, a rod mounted by means of a knuckle jointed hinge on the back edge of said plate and a handle adjustably mounted on said rod.

6. In a paperhangers' tool, the combination of a flat plate of relatively narrow width in proportion to its length, a plurality of longitudinally arranged grooves in parallel relation to the front edge of said plate and to each other, said grooves being located at predetermined distances from said front edge of said plate, a rod mounted by means of a knuckle jointed hinge on said plate a handle adjustably mounted on said rod, and a spike carried by the free end of said handle.

7. A paperhangers' trimming appliance comprising a flat plate of rectangular form and of relatively narrow width in proportion to its length, a series of grooves longitudinally arranged in one of the faces of said plate in parallel relation to one of the longer edges of said plate and to each other, said grooves being located at predetermined distances from the said longer edge of said plate, a bracket detachably mounted on said plate, and an adjustable handle pivoted to said bracket.

8. A paperhangers' trimming appliance comprising a flat plate of rectangular form and of relatively narrow width in proportion to its length, a series of grooves longitudinally arranged in one of the faces of said plate in parallel relation to the front edge of said plate and to each other, said grooves being located at predetermined distances from said front edge of said plate, a bracket detachably mounted on the back edge of said plate, a rod pivoted to said bracket, a handle adjustably mounted on said rod, and a spike mounted on the free end of said handle.

WILLIAM BOOTH LUPTON.
